UNITED STATES PATENT OFFICE.

ROBERT S. BRENNER, OF UNION CITY, NEW JERSEY, AND JOHN SCOTT, OF STAPLETON, NEW YORK, ASSIGNORS TO STANDARD OIL DEVELOPMENT COMPANY, A CORPORATION OF DELAWARE.

DESIGN FOR A SIGN.

Application filed June 19, 1928. Serial No. 27,202. Term of patent 14 years.

To all whom it may concern:

Be it known that we, ROBERT S. BRENNER, a citizen of the United States, residing at Union City, in the county of Hudson and State of New Jersey; and JOHN SCOTT, a citizen of the United States, residing at Stapleton, Staten Island, in the county of Richmond and State of New York, have invented a new, original, and ornamental Design for Signs, of which the following is a specification, reference being had to the accompanying drawing, forming part thereof.

The figure is a front elevation of a sign, showing our new design.

We claim:

The ornamental design for a sign, as shown.

ROBERT S. BRENNER.
JOHN SCOTT.
